INSULATOR

Eugene H. Fischer, Derry, Pa.

Application December 4, 1931, Serial No. 578,889

4 Claims. (Cl. 173—318)

My invention relates to insulators and particularly to suspension insulators of the cap-and-pin type.

It is an object of my invention to provide an insulator wherein the various elements are so disposed and shaped that the internal forces are distributed to materially improve the strength and durability of the insulator.

Figure 1, of the accompanying drawing, is a view in side elevation of an insulator embodying my invention, and

Fig. 2 is an enlarged detail view, partially in elevation and partially in section of a portion of the insulator of Fig. 1.

15 The insulator comprises, in general, a dielectric element 2, a cap terminal element 3 and a pin terminal element 4 all disposed in a usual substantially telescopic or interfitting relation.

The dielectric element 2, preferably of porcelain, comprises a surface creepage flange 6 and a head portion of substantially cup-shape having an end wall 8 and a longitudinal side wall 9 from the open end of which the flange 6 diverges.

The inner and outer surfaces of the side wall 9 are provided with laterally-extending longitudinally-spaced projections 10 constituting, in effect, annular ridges formed, preferably, by rolling while the porcelain is in the plastic state.

Obviously, such projections may be in the form 30 of a single continuous helical ridge or a multiplicity of annularly discontinuous projections, such as might be provided by sand or other particles glazed in position.

The first few of the ridges or projections 10, from the top down, on the inner surface, and from the bottom up, on the outer surface, of the wall 9, are of gradually increasing lateral extent and the remainder thereof are preferably of substantially the same lateral extent substantially equal to the greatest of the graded projections.

The cap terminal 3, preferably of metal, has a usual socket portion 12 at its upper closed end for attachment to a ball head, similar to the ball head 14 of the metal pin 4, of the next adjacent insulator or other member with which the insulator cooperates. Other means, such as the usual clevis, may be substituted for the socket portion 12.

50 The cap 3 further comprises a plurality of annular inner-surface steps 15, extending upwardly from its lower end, that slope relative to the longitudinal axis of the insulator and appear as substantially parallel lines in any vertical plane through the longitudinal axis of the in-

sulator, as shown adjacent to the right-hand side of Fig. 2. An annular surface between the surfaces 15 is represented by a line 16 that is substantially normal to the lines representing the surfaces 15.

5 The pin 4 comprises an enlarged head 17 having a downwardly and inwardly-sloping surface 18, a shank 20 joining the head 17 and extending to the ball head 14 thereof. A portion of the shank 20 is preferably slightly tapered so that its diameter is slightly less adjacent to the head 17 than at the exposed portion of the shank.

Yieldable elements 22 and 23, of usual character, are disposed, respectively, between the cap and the dielectric head and between the dielectric head and the pin.

Molded bodies 24 and 25, preferably of cement, are, respectively, disposed between the cap and the dielectric head and between the dielectric head and the pin.

20 In the above-described structure, the surfaces 18 and 15 are substantially parallel, so that opposite longitudinal forces, in this case tension forces, on the cap and pin terminals are normally translated into substantially parallel compression forces between, and normal to, the surfaces 15 and 18 for a substantial distance along the insulator.

The surface 18 is slightly curved to compensate for the different radial thicknesses of the molded 30 body 25. The upper part of the surface 18 imposes less stress on the thin section of the body 25 by reason of the fact that it more nearly approaches parallelism to the inner surface of the wall 9, and the remaining portion of the surface 18 imposes gradually more stress, as the body 25 increases in thickness. This construction is provided to prevent cracking of the porcelain adjacent to the intersection of the walls 8 and 9.

The surfaces 15 may also be slightly curved 40 but, by reason of the greater diameter and mass of the molded body 24, such curvature does not make sufficient practical difference to warrant the added expense.

The surfaces 15, being radially offset with the surface 16 therebetween normal thereto in the direction of the compression forces, act as a single surface beginning at the lower edge of the cap and extending as far as the upper end of the upper surface 15 but are offset to reduce the bulk of the molded body 24 and to render the latter of more uniform radial thickness. This feature tends toward uniformity of compression in all of the material between the surfaces 15 and 18.

However, the top of the surface 18 is above the top inner ridge 10 and the bottom of the lower surface 15 is below the lower outer ridge 10. If, in view of this feature, the ridges 10 were all of the same lateral extent, or, if there were no ridges at all, there would be sharp lines of demarcation in the dielectric and molded bodies between the zone where these bodies are traversed by the diagonal compression forces and the portions above and below this zone. Thus, by grading the ridges, as described, there is a more gradual introduction of the diagonal compression forces into this zone from above and from below, there being still a substantial thickness of the frusto-conical compression zone in which the forces are substantially equal or uniform. A similar effect may be obtained by varying the slope of the side surfaces of the ridges, the distances therebetween, or by a combination of these features.

It is contemplated to fill the spaces between the ridges 10, when metallic glaze is employed on the dielectric surface and solder is employed as the molded bodies, because this construction is of exceptional strength along the dielectric surface, but, when cement, or similar material is employed, ridges or sand particles are provided to add shearing strength.

There is a substantial quantity of the molded body 25, adjacent to the lower inner portion thereof, that is of little benefit, so far as adding to the efficiency of the insulator is concerned, but it is not commercially efficient to remove it or to substitute other material in its place. It ordinarily clings to the shank 20 so that, under heavy load, when the pin 4 pulls out of its original position by an infinitesimal amount, cracks are caused in the body 25 below its compression zone and transmitted upwardly into this zone.

By slightly divergently tapering the shank from the head 17 downwardly, the above-mentioned cracking is avoided by causing the shank to pull away from the cement body.

While I have shown and described particular forms of my invention, changes may be effected therein without departing from the spirit and scope thereof, as set forth in the appended claims.

I claim as my invention:

1. A suspension insulator comprising a dielectric member of substantially inverted cup-shape, a cap member surrounding the top and side wall of said dielectric member and having an inwardly sloping peripheral flange, a load-receiving pin having an enlarged head portion disposed within said dielectric member, and bodies of molded material disposed between said members for maintaining them in spaced relation, the peripheral flange on said cap and the enlarged head portion on said pin being so proportioned and related that tensional forces acting on said pin result in forces of compression between said pin and cap through the side wall of said dielectric member, and means on the inner and outer faces of said side wall for grading the distribution of said compressional forces along said side walls, said means comprising a series of annular ridges rounded in cross-section and of graded lateral dimension projecting into the molded material.

2. A suspension insulator comprising a dielectric member of substantially inverted cup-shape, a metallic cap surrounding the top and side wall of said dielectric member and having an inwardly sloping peripheral flange, a load-receiving pin having an enlarged head portion disposed within said dielectric member, and bodies of molded material disposed between said members for maintaining them in spaced relation, the peripheral flange on said cap and the enlarged head portion on said pin being so proportioned and related that tensional forces acting on said pin result in forces of compression between said pin and cap through the side wall of said dielectric member, and means on a face of said side wall for grading the distribution of said compressional forces along said side wall axially of the insulator, said means comprising a series of annular ridges rounded in cross-section rolled into the side wall of said dielectric member and varying in height from a minimum adjacent to an edge of the ridged portion.

3. A suspension insulator comprising a dielectric member of substantially inverted cup-shape, a metallic cap surrounding the top and side wall of said dielectric member and having an inwardly sloping peripheral flange, a load-receiving pin having an enlarged head portion disposed within said dielectric member, and bodies of molded material disposed between said members for maintaining them in spaced relation, the peripheral flange on said cap and the enlarged head portion on said pin being so proportioned and related that tensional forces acting on said pin result in forces of compression between said pin and cap through the side wall of said dielectric member, and means on a face of said side wall for grading the distribution of said compressional forces along said side wall axially of the insulator, said means comprising a series of annular ridges presenting in profile a smooth sinuous contour and varying in height from a minimum height at an edge of the ridged area.

4. A suspension insulator comprising a dielectric member of substantially inverted cup-shape, a metallic cap surrounding the top and side wall of said dielectric member and having an inwardly sloping peripheral flange, a load-receiving pin having an enlarged head portion disposed within said dielectric member, and bodies of molded material disposed between said members for maintaining them in spaced relation, the peripheral flange on said cap and the enlarged head portion on said pin being so proportioned and related that tensional forces acting on said pin result in forces of compression between said pin and cap through the side wall of said dielectric member, and means on a face of said side wall for grading the distribution of said compressional forces along said side wall axially of the insulator, said means comprising a series of annular ridges rolled into the side wall and varying in height from a minimum adjacent to an edge of the ridged portion.
